Specification of Letters Patent.

Patented Apr. 16, 1912.

Application filed August 11, 1909. Serial No. 512,323.

To all whom it may concern:

Be it known that I, ARISTIDES REYNOLDS MURRAY, a citizen of the United States, residing at Cincinnati, in the county of Hamilton and State of Ohio, have invented certain new and useful Improvements in Shaping-Machines, of which the following is a specification.

My invention relates to shaping machines, and has for its object the provision of new and improved means for accomplishing and controlling the feed of the tool toward the work, and the invention will be readily understood from the following description and claims, and from the drawings, in which latter:

Figure 1 is a side elevation of so much of a shaping machine as is necessary to illustrate my invention. Fig. 2 is a front elevation of the same. Fig. 3 is a plan view of the same. Fig. 4 is an enlarged side elevation of the tool end of the tool-ram and guideway, partly broken away, and partly in vertical section on the line $z-z$ of Fig. 2. Fig. 5 is a vertical cross-section taken on the line $y-y$ of Fig. 4. Fig. 6 is an enlarged axial section on the line $y-y$ of Fig. 4 showing the mounting for the ratchet-wheel. Fig. 7 is a detail in horizontal section on the line $x-x$ of Fig. 4; and, Fig. 8 is a detail in vertical section on the line $w-w$ of Fig. 4.

1 represents the column, on which the tool-ram 2 is caused to reciprocate in a guideway 3 in any ordinary or well-known manner. For accomplishing this reciprocation I have shown a crank-arm 5 integral with a gear 6, a pinion 7 operated by a drive-shaft 8 meshing with the gear.

9 is a crank-block adjustable in a guideway 10 of the crank-arm by a screw-rod 11, the crank-pin 12 of the crank-block being journaled in a slide-block 13 having movement in a guideway 14 of a rocker-arm 15 pivoted on a shaft 16 to the column and provided with slots 17 encompassing anti-friction rollers 18 on pins 19 on a positioning block 20 adjustable lengthwise of the tool-ram by a screw 21 and secured in adjusted positions by a clamp 22. The adjustment of the crank-block adjusts the length of stroke of the ram, and the adjustment of the positioning-block determines the location of stroke of the ram.

25 is a swivel-block having a trunnion 26 journaled in the bearing 27 at the forward

end of the ram. The swivel-block carries a tool-slide 28 on which a tool 29 is adapted to be suitably secured. The tool-slide is adjustable toward and from the work, which is arranged to be supported on a table 30, 60 there being a guideway 31 between the tool-slide and the swivel-block. The adjustment of the tool-slide is accomplished by means of a screw-rod 32 having threaded bearing 33 in the swivel-block, the screw-rod being held against endwise movement in a bearing 34 of the tool-slide. The swivel-block is arranged to be adjusted about its axis for presenting the tool either in vertical or angular position to the stock being operated on, and held in adjusted position by a clamp-block 35 received in an annular groove 36 of the swivel-block, into which it is forced by a set-screw 37.

41 is a bevel-gear journaled against endwise movement in a bearing 42 of the swivel-block and having spline-connection 43 with the screw-rod.

44 is a longitudinal shaft whose rotary axis is coincident with the swiveling axis of 80 the swivel-block 25 and which has at its forward end a bevel-gear 45 which meshes with the bevel-gear 41 and at its rear end a spiral gear 46 which meshes with a spiral gear 47 on a cross-shaft 48 to which a bush- 85 ing 49 is secured, as by a key 50.

51 is a ratchet-wheel encompassing the bushing 49, the ratchet-wheel having frictional engagement with the bushing for causing the cross-shaft 48 to rotate with the 90 ratchet-wheel during the ordinary resistances of the tool feed, the ratchet-wheel being however permitted to rotate with relation to said cross-shaft upon the presence of greater resistance than that necessary to 95 accomplish the ordinary tool-feed. Thus the bushing is provided with a flange 52, the ratchet-wheel with an internal flange 53, there being a collar 54 having a flange 55, the flange of the ratchet-wheel being received between the flanges of the bushing and collar, with friction-disks 56 located between the flange of the ratchet-wheel and the flanges of the bushing and collar. The collar has spline-connection 57 with the 100 bushing. A nut 58, threaded to the bushing, permits adjustment of the frictional resistance between the ratchet-wheel and bushing.

61 is a pawl-bracket provided with a slot 110

62 through which a securing-bolt 63 is arranged to be received in selective threaded apertures 64 located at suitable distances apart lengthwise of the guideway for the 5 tool-ram, and for readily positioning said pawl-bracket the same is provided with a longitudinal lug 65 adapted to rest upon the upper face of the top-bar 66 of said guideway. The bracket is provided with an upward extension 67 to which an arm 68 is pivoted on a bolt 70, the arm being provided with a multi-tooth pawl 71, the teeth of which are located in a plane substantially parallel with the direction of reciprocation 10 of the ratchet-wheel, and substantially in line with the tooth of the ratchet-wheel, located at a point in the periphery of the ratchet-wheel intersected by a radial line at right angles to the path of reciprocation of 15 the ratchet-wheel, being in the present instance the lowermost tooth of the ratchet-wheel.

As the ratchet-wheel advances toward the multi-tooth pawl, in the idle stroke of the 20 ram, the direction of which is indicated by the arrow α , engagement will thus be successively had between a plurality of teeth of the ratchet-wheel and a plurality of teeth of the multi-tooth pawl, preferably without 25 substantially moving the teeth of the multi-tooth pawl out of said plane in line with said lowermost tooth of the ratchet-wheel. The construction is such that, irrespective of the extent of the arc through 30 which the ratchet-wheel is caused to turn at each step of movement, the turning force will be continuously exerted upon the ratchet-wheel substantially at the point in its periphery and in the direction which 35 will require least power for effecting the turning and also permit the greatest range of movement at each reciprocation of the ratchet-wheel. In this manner the greatest 40 range in extent of feed with least jar upon the parts is provided.

For urging the multi-tooth pawl into engaging position with the ratchet-wheel, I provide a spring 75 received in a socket 76 of the arm 68 about a screw 77 threaded into 45 the lug 65 of the pawl-bracket at 78, whereby the rear end of the arm 68 is held down 50 yieldingly for maintaining the forward end of said arm having thereon the multi-teeth of the pawl into contacting range 55 with the ratchet-wheel, a bolt 79 being provided on said pawl-bracket against which the arm 68 is arranged to engage for limiting 60 this movement. The form of the teeth on the multi-tooth pawl and the ratchet-wheel is such that the ratchet-wheel may 65 pass forwardly over the multi-tooth pawl without causing operation of the ratchet-wheel when the tool-ram is moved in reverse direction for its cutting stroke. If it is desired to bring the multi-tooth pawl into in-

operative position, the end of the arm on which the same is located is depressed and held in depressed position by a set-screw 80 threaded in the bracket at 81 and received in a socket 82 of said arm.

In operation, if it is desired to accomplish the feed of the tool toward the work by means of power, the pawl-bracket 61 is positioned longitudinally of the slideway for the tool-ram so that one or more teeth 75 on the multi-tooth pawl may be engaged by a corresponding number of teeth on the ratchet-wheel during the idle stroke of the tool-ram, for accomplishing tool-feed in successive steps of desired extent, depending 80 on the number of teeth engaged. By the construction stated, the teeth of the ratchet-wheel, which sequentially arrive substantially in the radial plane of said ratchet-wheel which is at right angles to its path 85 of reciprocation, are engaged by the successive teeth of said multi-tooth pawl. The frictional resistance between the ratchet-wheel and the feeding connection for the tool-slide is such as to normally cause feed 90 of the tool upon the consequent operation of the ratchet-wheel. This tool-feed by successive steps will continue during the operation of the machine until a rod 85, which is adjustable lengthwise in a bearing 95 86 and held in adjusted position by a set-screw 87 on the tool-slide, strikes a lug 88 on the swivel-block, by which an adjustable stop for the tool-feed is provided, which overcomes the frictional resistance between 100 the ratchet-wheel and the cross-shaft, so that, even if the operation of the machine continues, the successive turns of the ratchet-wheel will not affect the tool-position, the ratchet-wheel thereafter simply 105 turning idly.

If it is desired to manually adjust the tool with relation to the work, the same may be accomplished by means of a hand-wheel 89 secured to the screw-rod 32, by which rotation is imparted to the screw-rod and the shafts connecting therewith for causing the screw-rod to turn irrespective of engagement of the ratchet-wheel with the multi-tooth pawl.

I have herein shown and described what appears to me to be the most advisable form of my invention, but it is obvious that changes in construction may be made without departing from the spirit of my invention.

Having thus fully described my invention, what I claim as new and desire to secure by Letters Patent is:

1. In a shaping machine, the combination 125 with a reciprocating ram and a tool-slide, of a rotative part having operative connection with said tool-slide for adjusting the same on said ram, a ratchet-wheel mounted on said ram and having operative connec- 130

- tion with said rotative part, a multi-tooth pawl with the successive teeth of which the successive teeth of said ratchet-wheel are arranged to make successive engagements, 5 the reciprocations of said ram moving said ratchet-wheel into and out of juxtaposition with said multi-tooth pawl, and means for causing inoperative relation between said pawl and ratchet-wheel during said last-named relations. 10
2. In a shaping machine, the combination with a reciprocating ram and a tool-slide, of a rotative part having operative connection with said tool-slide for adjusting the 15 same on said ram, a ratchet-wheel mounted on said ram and having frictional connection with said rotative part, a pawl with which the teeth of said ratchet-wheel are arranged to make successive engagements 20 for feeding said tool-slide on said ram with a step-by-step movement, the reciprocations of said ram moving said ratchet-wheel into and out of juxtaposition with said pawl, said frictional connection between said ratchet-wheel and rotative part 25 permitting cessation of movement of said tool-slide irrespective of continuing engagements between said ratchet-wheel and pawl. 30
3. In a shaping machine, the combination with a frame, a reciprocating ram, and a tool-slide, of a rotative part having operative connection with said tool-slide for adjusting the same on said ram, a ratchet-wheel mounted on said ram having operative connection with said rotative part, a multi-tooth pawl supported from said frame, the teeth of which are located in a plane substantially parallel with the path of travel of said ram and coincident with 35 the bottom of said ratchet-wheel for permitting engagements between successive teeth on said ratchet-wheel and pawl while said teeth on said pawl are maintained substantially in said plane during travel of 40 said ram in one direction for effecting a step-by-step feed of said tool-slide, means for adjusting said multi-tooth pawl lengthwise for determining the number of teeth thereon engaged by said ratchet-wheel, and 45 resilient means for permitting retraction of said multi-tooth pawl with relation to said ratchet-wheel during travel of said ram in the opposite direction, the reciprocations of said ram moving said ratchet-wheel into 50 and out of juxtaposition with said multi-tooth pawl. 55
4. In a shaping machine the combination with a ram and tool-slide, of a rotative part having operative connection with said tool-slide for adjusting the same on said ram, a ratchet-wheel having operative connection with said rotative part, a multi-tooth pawl, an adjustable bracket on which the same is mounted, means between said pawl and bracket for normally urging said pawl into 60 the range of said ratchet-wheel, and positioning means between said pawl and bracket for locating said pawl in inoperative position with relation to said ratchet-wheel. 65
5. In a shaping machine, the combination with a ram and tool-slide, of a rotative part having operative connection with said tool-slide for adjusting the same on said ram, a train of means for intermittently rotating said rotative part with a step-by-step movement coincident with the reciprocating movements of said ram, said last-named train of means comprising a friction drive-connection, and adjustable stopping means for said tool-slide causing stoppage of part 70 of said train of means for causing relative movement between elements of said friction drive-connection while maintaining said friction drive-connection in driving relation. 75
6. In a shaping machine, the combination with a frame, a ram, and a tool-slide, of a rotative part having operative connection with said tool-slide for adjusting the same on said ram, a ratchet-wheel mounted on 80 said reciprocating ram and having frictional operative connection with said rotative part, a multi-tooth pawl, the teeth of which extend in a line parallel to the path of reciprocation of said ratchet-wheel and coincident with the tooth-position of the tooth of said ratchet-wheel in said line which is farthest removed from the rotary axis of 85 said ratchet-wheel, and means for permitting yielding of said pawl upon retractive movement of said ratchet-wheel. 90
7. In a shaping machine, the combination with a frame, a ram and a tool-slide, of a rotative part having operative connection with said tool-slide for adjusting the same on said ram, a ratchet-wheel having operative connection with said rotative part, a bracket adjustable on said frame, a pawl-bar pivoted on said bracket, a multi-tooth pawl for said ratchet-wheel on said pawl-bar, and a spring between said bracket and 95 pawl-bar for normally urging said multi-tooth pawl into range of said ratchet-wheel, substantially as described. 100
8. In a shaping machine, the combination with a frame, a ram and a tool-slide, of a rotative part having operative connection with said tool-slide for adjusting the same on said ram, a ratchet-wheel having operative connection with said rotative part, a bracket adjustable on said frame, a pawl-bar pivoted on said bracket, a multi-tooth pawl for said ratchet-wheel on said pawl-bar, a spring between said bracket and 110 pawl-bar for normally urging said multi-tooth pawl into range of said ratchet-wheel, and means for positioning said pawl-bar for locating the multi-tooth pawl thereon out of range of said ratchet-wheel, substantially as described. 115
9. In a shaping machine, the combination with a frame, a ram and a tool-slide, of a rotative part having operative connection with said tool-slide for adjusting the same on said ram, a ratchet-wheel having operative connection with said rotative part, a bracket adjustable on said frame, a pawl-bar pivoted on said bracket, a multi-tooth pawl for said ratchet-wheel on said pawl-bar, a spring between said bracket and 120 pawl-bar for normally urging said multi-tooth pawl into range of said ratchet-wheel, and means for positioning said pawl-bar for locating the multi-tooth pawl thereon out of range of said ratchet-wheel, substantially as described. 125
10. In a shaping machine, the combination with a frame, a ram and a tool-slide, of a rotative part having operative connection with said tool-slide for adjusting the same on said ram, a ratchet-wheel having operative connection with said rotative part, a bracket adjustable on said frame, a pawl-bar pivoted on said bracket, a multi-tooth pawl for said ratchet-wheel on said pawl-bar, a spring between said bracket and 130 pawl-bar for normally urging said multi-tooth pawl into range of said ratchet-wheel, and means for positioning said pawl-bar for locating the multi-tooth pawl thereon out of range of said ratchet-wheel, substantially as described. 130

9. In a shaping machine, the combination with a ram and tool-slide, of a rotative part having operative connection with said tool-slide for adjusting the same on said ram, a train of means for intermittently rotating said rotative part with a step-by-step movement coincident with the reciprocating movements of said ram, said last-named train of means comprising a friction drive-connection, means for adjusting the driving power of said friction drive-connection, and adjustable stopping means for said tool-slide causing stoppage of part of said train of means for causing relative movement between elements of said friction drive-connection while maintaining said friction drive-connection in driving relation.
10. In a shaping machine, the combination with a reciprocating ram and a tool-slide, of a rotative part having operative connection with said tool-slide for adjusting

the same on said ram, a ratchet-wheel mounted on said ram and having operative connection with said rotative part, a multi-tooth pawl with the successive teeth of which the successive teeth of said ratchet-wheel are arranged to make successive engagements, means for adjustably positioning said multi-tooth pawl lengthwise of said ram for determining the number of teeth thereof engaged by said ratchet-wheel, the reciprocations of said ram moving said ratchet-wheel into and out of juxtaposition with said multi-tooth pawl.

In testimony whereof, I have signed my name hereto in the presence of two subscribing witnesses.

ARISTIDES REYNOLDS MURRAY.
